INVENTOR.

C. P. Jacobs

UNITED STATES PATENT OFFICE.

CHARLES P. JACOBS, OF INDIANAPOLIS, INDIANA.

LATH-STRIP.

SPECIFICATION forming part of Letters Patent No. 350,488, dated October 12, 1886.

Application filed January 25, 1886. Serial No. 189,725. (No model.)

To all whom it may concern:

Be it known that I, CHARLES P. JACOBS, a resident of Indianapolis, Indiana, have made certain new and useful Improvements in 5 Sheathing-Laths, a description of which is set forth in the following specification, reference being made to the accompanying drawings, in the several figures of which like letters represent like parts.

10 My invention relates to the construction of strips which are intended to be used both as lath and sheathing for walls and ceilings, and will be understood from the following description.

15 In the drawings, Figure 1 represents a perspective view of several of the pieces nailed to the studding, one above the other, a portion of the plaster in place, the remainder being torn away to show the relative location of 20 the parts. Fig. 2 represents a vertical section along the line of the studding in Fig. 1.

In detail, *b* is the lath-strip, made in the shape indicated, one portion being thicker than the other, the outer edge or side of the 25 thick portion being beveled, as shown, the thin portion being about half the thickness of the thick portion. The edge of the thin portion is cut away, as shown at *x*, Figs. 1 and 2, so that when one of these pieces is placed up- 30 on the other a groove is left between it and the beveled portion of the adjacent lath, whereby a key for holding the plaster, *p*, is formed on one side and a recess or groove is provided behind. This groove allows for the expansion 35 and contraction of the wood of which the lath-strip is composed, for when wet mortar is applied to the lath-strips, even if they are wholly or partly dry, the wood will swell, and there will be an expansion and subsequently a con-

traction of the wood, and this will cause the 40 plaster to crack unless some such groove is provided.

In nailing the strips upon the studding *s* it is necessary to nail the topmost one first, and then another is placed below it and shoved 45 up against it and nailed, and by this means small nails can be used, as they are only required to go through the thin portion of the lath.

I am aware that boards having dovetail 50 grooves cut in them to receive the plaster and intended to be used both as sheathing and lath, and that lath-pieces with one side made thinner than the other are not new, and I do not broadly claim the same as my invention. 55

What I do claim, however, as my invention, and desire to secure by Letters Patent, is the following:

1. The sheathing-lath *b*, one portion thicker than the other, the lower end of the thin portion cut away so as to leave an opening or groove between it and the next lath-strip, substantially as described. 60

2. A series of lath-pieces, their upper portion thicker than the lower, the latter cut away 65 so as to form a groove or opening between one lath-strip and the one below it, to allow for the expansion and contraction of the material behind the thicker portion of the other, these pieces nailed to studding, the whole forming 70 a wall or ceiling to receive plastering, substantially as described.

In witness whereof I hereinunto set my hand this 6th day of January, 1886.

CHARLES P. JACOBS.

Witnesses:

J. E. SCOTT,
HATTIE MURRY.
